UNITED STATES PATENT OFFICE.

FERDINAND O. HORSTMANN, OF PHILADELPHIA, PENNSYLVANIA, ASSIGNOR
TO HIMSELF AND WALTER HORSTMANN, OF SAME PLACE.

MASQUERADE-SUIT.

SPECIFICATION forming part of Letters Patent No. 433,732, dated August 5, 1890.

Application filed January 22, 1890. Serial No. 337,713. (No model.)

To all whom it may concern:

Be it known that I, FERDINAND ODEN HORSTMANN, a citizen of the United States, residing in Philadelphia, Pennsylvania, have 5 invented a certain Improved Masquerade-Suit, of which the following is a specification.

The object of my invention is to produce for the use of secret societies, masqueraders, and others a knit suit having the representation of a skeleton thereon, as fully described hereinafter, reference being had to the accompanying drawing, in which the figure represents the suit with the representation of a skeleton thereon.

15 The suit of knit goods is originally of a light color, white or gray being the natural color of the yarn, and the outline of the skeleton is produced by blocking out the form of the skeleton on the fabric and saturating the 20 fabric surrounding the blocked-out portion with a suitable dark dyeing solution, so that this surrounding portion will be of a dark color, preferably black, which, when the suit is worn in the dark, will be indistinct and the 25 light portion represent in strong lines the form of a skeleton.

I have shown in the drawing the suit incasing the feet. The hands may also be incased as well; but I prefer to make the suit with the 30 arm portions extending only to the wrist, exposing the wearer's hands, which may be incased in gloves.

In some cases the leg portions may only ex-

tend to the ankles; but I prefer to incase the feet, as shown.

35

To complete the representation of a skeleton, the wearer incases his head in a representation of a skull.

In some instances the design may be produced upon the back of the garment as well 40 as the front, in this case showing the rear view of the skeleton.

45 By the above means I am enabled to produce a suit that will be comfortable to the wearer, and the constant use of which will not in any way affect the durability of the representation of the skeleton other than that due to the wear of the fabric.

The shade lines on the skeleton itself to bring out the contour of the bones can be produced by tint-dyeing.

50 I claim as my invention—

As a new article of manufacture, a knit-goods suit having thereon the representation of a skeleton in the natural color of the wool 55 from which the suit is made, the surrounding portion of the suit outlining the skeleton being dyed a dark color, substantially as and in the manner set forth.

In testimony whereof I have signed my 60 name to this specification in the presence of two subscribing witnesses.

FERDINAND O. HORSTMANN.
